UNITED STATES PATENT OFFICE.

CHARLES H. PRINTZ, OF LURAY, VIRGINIA.

BELT ATTACHMENT.

Application filed September 13, 1921. Serial No. 500,305.

To all whom it may concern:

Be it known that I, CHARLES H. PRINTZ, a citizen of the United States, residing at Luray, in the county of Page and State of Virginia, have invented new and useful Improvements in Belt Attachments, of which the following is a specification.

It is a well known fact that belts have, to a material extent superseded suspenders for holding up men's trousers. These belts are provided with various classes of clamps or buckles, all of which being more or less ornamental. A large majority of these buckles are not of the common substantially rectangular frame construction with the pivoted tongue that passes through an opening in the belt end, ornamental being a desired quality in such devices, and as a consequence, the outer face of the buckle or clasp is generally in the nature of a longitudinally arched plate. It is possible, with the frame construction of buckles to attach the bar of a watch chain to the belt, but with the other class of buckles no means is provided whereby the bar may be secured thereon. Even in the first instance, the bar is not securely attached and must necessarily be removed when the belt is adjusted. Thus, as far as I am aware, there is no belt provided with means for securely attaching the bar of a watch chain thereto, it being the common and useful practice of arranging the watch in the watch pocket of the trousers.

It may therefore be considered the primary object of this invention to produce a belt having means thereon whereby the bar of a watch chain may be effectively supported thereon.

It is a further object to produce a means for effectively supporting the bar end of a watch chain on a belt which will add to the ornamental of the belt.

It is a still further object to produce a means for supporting the bar on the end of a watch chain from a belt in an easy, quick and efficient manner, said means being of an extremely simple construction which may be cheaply manufactured and which will add to the ornamental of the belt.

The foregoing, and other objects which will appear as the nature of the invention is better understood, may be accomplished by a construction, combination and arrangement of parts such as is disclosed by the

drawings which accompany and which form part of this specification.

In the drawings:—

Figure 1 is a view illustrating the application of the improvement.

Figure 2 is a fragmentary perspective view of the end of the belt provided with the improvement.

Figure 3 is an approximately central vertical transverse sectional view through the improvement and belt.

Referring now to the drawings in detail, the numeral 1 designates an ordinary leather belt commonly worn as a support for trousers. The belt, at one of its ends is provided with the usual buckle 2 to receive its opposite or tongue end 3.

The tongue portion of the belt at a suitable distance from its end has arranged thereon my improvement.

My improvement, in the preferred embodiment of my invention, is constructed from a single piece of substantially rectangular metal bent upon itself to entirely surround the belt. The strip of metal has one of its ends rounded upon itself to provide the same with a lip 4. This lip, from its bottom portion is provided with a rounded opening that communicates with a substantially rectangular opening 5 in the strip 6.

The portion of the strip provided with the opening forms the back plate of the improvement. This back plate is, of course, arranged in contacting engagement with the inner side of the belt, and is bent upon itself, as at 7, over the upper edge of the belt. The strip is then continued over the front face of the belt, and in contacting engagement therewith. This portion forms

the front plate of the improvement and is indicated by the numeral 8. The front 8 may be highly ornamented, if desired, or the entire device may be coated with a covering corresponding to that of the belt.

The front plate is bent inwardly over the lower edge of the belt, as at 9. The portion 9 is centrally formed with a tongue 10 that passes through the opening 5, contacting with the upper wall provided by the said opening, the said tongue being thence bent over the rear plate of the improvement and

may have its free end enter a suitable transverse depression 11 in the said back of the improvement. If desired, the back plate of the improvement may have on its inner face

inwardly directed prongs 16 which enter the belt and hold the housing portion of the improvement against sliding movement on the belt.

5 The bar, at the outer end of the chain which is attached to the watch to be worn in the watch pocket of the user of the belt, is indicated by the numeral 12. This bar is designed to be inserted through the opening in the bottom wall of the lip 4 and to also pass through the opening 5 in the back plate of the improvement and from thence be turned to permit of the same resting snugly in the lip. The chain 13, at the portion thereof attached to the bar passes freely through the rounded opening 14 in the lip, the said opening 14, of course, communicating with the opening 5, and preferably the lip, in a line with the said opening 14 is 10 depressed outwardly, as at 15 forming the said lip with an inner concaved portion that receives therein the usual central enlarged eye carrying member on the bar 12 to which the chain 13 is directly attached.

15 25 A device, as above described will not interfere with the proper adjustment of the belt, but will add to the ornamentality thereof. The chain bar, when arranged in the lip of the improvement cannot be accidentally removed, and thus the improvement provides a means for more effectively protecting a watch from theft. The device is of an extremely simple construction, may be cheaply manufactured, and readily attached to any ordinary construction of belts.

30 35 It is, of course, to be understood that in the manufacture of the improvement, I may make changes from the construction herein illustrated and described, and therefore it is to be understood that such changes and variations may be made therefrom as fall 40 within the scope of what I claim.

Having described the invention, I claim:—

45 1. In combination with a belt, of a plate

bent upon itself to provide a substantially rectangular housing which receives therethrough the belt, means holding said housing against movement on the belt, said housing having a rear extending portion which is 50 bent upon itself to provide a cross sectionally U-shaped lip, said lip and the back of the housing having aligning openings designed to receive therethrough the bar of a watch chain to permit of the said bar resting 55 in the lip, and said lip, at the opening therein, being depressed outwardly, for the purpose set forth.

2. In combination with a belt, of means for attaching thereto and supporting therefrom the bar of a watch chain, said means comprising a strip having one of its ends bent upon itself to provide a cross sectionally rounded lip, said lip and strip having communicating openings, said strip being arranged against the inner face of the belt and bent over the upper edge thereof against the outer face and under the lower edge of the belt, said last mentioned portion of the strip having a tongue which is extended 70 through the opening and which is bent against the rear face of the strip.

3. In combination with a belt, of means for attaching thereto and supporting therefrom the bar of a watch chain, said means 75 comprising a strip having one of its ends bent upon itself to provide a cross sectionally rounded lip, said lip and strip having communicating openings, said strip being arranged against the inner face of the belt 80 and bent over the upper edge thereof against the outer face and under the lower edge of the belt, said last mentioned portion of the strip having a tongue which is extended through the opening and which is bent 85 against the rear face of the strip, and said rear face having a depression to receive therein the end of the tongue.

In testimony whereof I affix my signature.

CHARLES H. PRINTZ.
